2,011,199

TREATMENT OF ALIPHATIC AND CYCLIC
SATURATED HYDROCARBONS

Joseph J. Pelc, Chicago, Ill.

No Drawing. Application August 17, 1934,
Serial No. 740,350

28 Claims. (Cl. 260—138)

This invention relates to the direct treatment of aliphatic and cyclic saturated hydrocarbons, either pure or as they occur in mixture in crude petroleum and distillate fractions thereof, to produce directly therefrom saturated alcohols and other compounds as will more fully hereinafter appear.

Various attempts have been made heretofore to convert saturated hydrocarbons present in crude petroleum and in distillate fractions thereof into alcohols, aldehydes and other compounds. For example, treatment with nitric acid and also by chlorination has heretofore been proposed. However, these attempts have not been entirely successful and, so far as I am aware, there has not been proposed any method for the direct production from saturated hydrocarbons of the character referred to of compounds such as alcohols, aldehydes, and other compounds of the type referred to below. As a result of extensive research and experimentation I have developed a method of producing directly from aliphatic and cyclic saturated hydrocarbons numerous useful compounds, and it is to this method that the present invention relates.

The principal object of the present invention is the direct production of certain important products from aliphatic and cyclic saturated hydrocarbons, and particularly from crude petroleum or distillate fractions thereof.

An important object of the present invention is to provide for the direct production of saturated aliphatic alcohols from saturated aliphatic hydrocarbons.

Another object of the invention is to provide for the direct production of cyclic saturated alcohols from cyclic saturated hydrocarbons, i. e. cycloparaffins.

A further object of the invention is to provide for the direct production of aliphatic aldehydes from saturated aliphatic hydrocarbons.

A further object of the present invention is to provide for the direct production from saturated aliphatic hydrocarbon and from cycloparaffins of unsaturated, double-bonded hydrocarbons or substituted alkynes formed by the addition of the aliphatic ketonic or aldehydic residue through the common aldehydic or ketonic group, i. e. the carbonyl group.

A further object of the invention is to provide for the direct production from saturated aliphatic hydrocarbons of alkynes having the same number of carbon atoms as the original saturated aliphatic hydrocarbons.

A further object of the present invention is to

provide for the direct production of compounds of the character referred to above not only from pure saturated hydrocarbons but especially from mixtures thereof as they occur in crude petroleum or any fraction or fractions of crude petroleum.

A further object of the invention is to provide for the direct production of unsaturated, double-bonded compounds or drying oils, which are essentially alkynes, or of oils containing mixtures of such unsaturated, double-bonded compounds with aliphatic alcohols or aldehydes, such materials being directly produced from crude petroleum or any fraction or fractions of crude petroleum, the said oils being adapted for use in crude or purified state as motor or fuel oils, in paints and lacquers, as solvents, perfumes, etc., or to be subjected to further treatment to produce pure fatty acids therefrom.

A further object of the present invention is to provide for the direct production of condensation products by the use of aliphatic ketones, or of polymerization products by the use of aliphatic aldehydes, from pure saturated hydrocarbons or mixtures thereof in crude petroleum or its fractions, such condensation and polymerization products being suitable for use in the production of resins and similar useful products.

A further object of the invention is to provide a method by which there can be produced directly from, and without any previous treatment of, saturated hydrocarbons, such compounds as alcohols, aldehydes and other compounds which can be readily purified, isolated and treated further to produce such products as fatty acids, for example.

A further object of the invention is to provide a method by which compounds analogous to those just referred to can also be produced directly, as far as they are structurally possible, from cycloparaffins.

Other objects and advantages of the present invention will become apparent during the course of the following description.

In its broad aspect the present invention consists of reacting a saturated aliphatic hydrocarbon or a cyclic saturated hydrocarbon with an aliphatic aldehyde or ketone in the presence of an activating agent. According to the manner in which the reaction is regulated and controlled, various products may be produced as will more fully hereinafter appear.

As indicated above, the present invention provides for the treatment of aliphatic saturated hydrocarbons, that is, the group of hydrocarbons having the type formula C_nH_{2n+2} , such as meth-

ane, ethane and the like. The invention is also adapted for the treatment of cyclic saturated hydrocarbons, i. e. cycloparaffins, having the type formula C_nH_{2n} , such as cyclopropane, cyclobutane, cyclopentane, cyclohexane and the like. As is indicated above, pure hydrocarbons of the above referred to character may be treated according to the present invention but the invention is particularly concerned with the treatment of mixtures of such hydrocarbons as they appear in crude petroleum and distillate fractions thereof, such as kerosene, gasoline, petroleum ether and the like.

As indicated above, the saturated hydrocarbon or mixture of hydrocarbons is reacted with an aliphatic aldehyde or ketone. While any aliphatic aldehyde may be employed in the practice of the process I prefer to employ para- and meta - aldehydes, such as paraformaldehyde, metaformaldehyde, paraldehyde and the like, and preferably paraldehyde. Similarly, various ketones may be used such as acetone, diethylketone, ethylmethylketone, and such compounds as substituted ketones in the nature of hydroxyacetone, but I prefer to employ acetone because of its complete suitability and relatively low cost.

As pointed out above, the reaction between the saturated hydrocarbon under treatment and the aliphatic aldehyde or ketone is effected in the presence of an activating agent. The activating agent may consist of an elevated temperature, preferably of the order of 500°-800° C. In other words, the reaction may be effected by heating the hydrocarbon with the reacting agent to a relatively high temperature. In this case the heat to which the materials are subjected serves as an activating agent to promote the reaction.

Instead of the use of heat as an activating agent, I may use certain chemical compounds as activating agents, in which case it is not necessary to effect the reaction at an elevated temperature. The chemical compound serving as an activating agent for the reaction may be a catalyst such as inorganic oxides and hydroxides, halogen acids, or sulfur oxides and sulfuric acid or mixtures thereof. I may also employ an activating agent consisting of inorganic halides other than alkali metal halides. Such halides serve in effect as catalysts although they do not act strictly as catalysts since they react to form halides with the organic compounds present. However, these halides formed are very readily broken down and the halides may be recovered in their original form. Thus, in the case of all of the chemical activating agents employed, the chemical compounds used may be substantially completely recovered and reused in the further practice of the process.

Referring to the chemical activating agents which may be used in the practice of the process, as an inorganic oxide I may employ soda lime, calcium oxide or the like. Caustic soda is the hydroxide preferably employed although other inorganic hydroxides such as potassium hydroxide, calcium hydroxide or the like may be used. Any inorganic halide except alkali-metal halides may be used as an activating agent. Calcium chloride and beryllium chloride are examples. Any of the halogen acids such as hydrochloric acid, hydrobromic acid or the like may be used. When any of the foregoing chemical activating agents are employed they must be used in great excess, generally to the extent of four times or more the volume of the mass of organic reacting agents present.

Where the reaction between the saturated hydrocarbon and the aliphatic aldehyde or ketone is effected in the presence of an activating agent comprising heat or one of the chemical activating agents just referred to, the yields are so small that the process may scarcely be said to be of commercial importance. However, for the sake of completeness several examples of the process using such activating agents will be set forth.

The process assumes real commercial importance when the activating agent employed is a sulfur oxide or sulfuric acid, or mixtures thereof. For example, sulfur dioxide or sulfur trioxide may be introduced in gaseous form into the reacting mass. However, in commercial practice I prefer to employ a relatively strong sulfuric acid as the activating agent. As will hereinafter appear, sulfuric acid of various strengths may be employed.

In commercial practice I prefer to react crude petroleum or a distillate fraction thereof with acetone or paraldehyde in the presence of sulfuric acid. By the control of the operating conditions, such as time, temperature, proportions of ingredients, etc., several different compounds can be produced as a result of the reaction. Examples of several such modifications will be hereinafter set forth in detail.

While it is more of scientific interest than of commercial importance, saturated alcohols may be produced by mixing an aliphatic saturated hydrocarbon or a cycloparaffin with an aliphatic ketone or aldehyde and heating the mixture at an elevated temperature, say from 500° to 800° C. Instead of treating the hydrocarbons themselves, mixtures of the same may be treated. For example, equal parts of gasoline and acetone or acetaldehyde are mixed in solution or in the form of an intimate suspension and the solution or mixture passed once or repeatedly through a tube or pipe, or heated in sealed tubes, at say from 500° to 800° C. As a result of this treatment certain amounts of aliphatic alcohols are produced, the treated mass containing not only the aliphatic alcohols but also a portion of the substances originally used in undecomposed condition, polymerization or condensation products, and also unsaturated, double-bonded compounds derived from the saturated hydrocarbons treated.

It may be here pointed out that the reactions which take place as well as all of the reactions described below are based essentially upon the reactivity of the carbonyl group

(-C=O)

which is common to both aldehydes and ketones. For this reason the reactions of both the aliphatic aldehydes and ketones are hereinafter jointly treated.

While there is a certain yield of desirable products such as aliphatic alcohols when the above referred to reaction is effected at an elevated temperature, better yields are obtained when the reaction is effected in the presence of an activating agent such as inorganic oxides, hydroxides or halides, such as chlorides, excepting alkali-metal halides. Where halides are employed they should be absolutely dry. Yields are increased if the saturated hydrocarbons or their mixtures are dissolved in the respective aliphatic aldehydes or ketones and the mass is supersaturated or impregnated with an inorganic oxide, hydroxide, or dry halide by vigorous mixing.

In some cases, especially when aliphatic aldehydes are employed, polymerization products predominate in the reaction mass after neutralization, as hereinafter referred to, but nevertheless alcohols and unsaturated, double-bonded compounds can be isolated either directly or by depolymerization of the product of polymerization between the aliphatic aldehyde and saturated hydrocarbon.

As an example of the use of a hydroxide as an activating agent for the reaction between the saturated hydrocarbon and the aliphatic aldehyde or ketone, I may mix about one part by weight of kerosene with three or more parts by weight of an aliphatic ketone. While, as stated above, I may use any aliphatic aldehyde or any aliphatic ketone, diethyl ketone may be mentioned for the purpose of specific illustration. This material is vigorously mixed with the kerosene as by mechanical stirring. To the mixture is then added not less than two or three parts by weight of dried sodium hydroxide, say in flakes. The amount of caustic soda employed may vary somewhat but it should be used in sufficient amount to make the mixture nearly solid. The resulting mixture is introduced into a vessel which is covered tightly to exclude air and moisture therefrom. The mixture is kept out of contact with the air for not less than one week with occasional addition of more caustic soda if the mixture starts to liquefy. At the end of about one week the mixture may be removed from the vessel and dissolved in water, in which case the mass will contain the products of the kerosene hydrocarbons such as unsaturated double-bonded hydrocarbons, alcohols, such for example, as decyl alcohol and double-bonded additive compounds of cycloparaffins and the ketone such, for example, as 1,1 dimethylcyclopentylethylene. If, instead of keeping the mixture for only about one week before dissolving it in water it is kept longer, say about two weeks, the reaction mass usually dissolves completely in water and on neutralization with acid, such as an inorganic acid, yields organic acids of the respective hydrocarbons of kerosene including naphthenic acids. The ketone present is usually also oxidized in this case to a mixture of acids.

The same process as just described may be repeated with crude petroleum or any fraction of crude petroleum. Where gaseous hydrocarbons are employed they generally require larger quantities of the aliphatic aldehydes or ketones, since they must be kept in solution. Some aliphatic aldehydes give only very small quantities of alcohols and unsaturated compounds from the saturated hydrocarbons used.

The foregoing process is somewhat faster when the reaction is conducted in the presence of inorganic oxides, for example, alkali metal oxides. It is also faster when certain chlorides, such as beryllium chloride, are employed as activating agents although with some chlorides the reaction is very slow. However, in principle the reactivity of the carbonyl group causes in all of these cases the formation of certain amounts of alcohols and unsaturated compounds, and condensation or polymerization products from the saturated hydrocarbons or cyclic paraffins.

When a halogen acid is employed as an activating agent and especially when it is used in gaseous form by dissolving the hydrogen halide in either the hydrocarbon or the aliphatic aldehyde or ketone, the yields of the alcohols and other com-

pounds from the saturated hydrocarbons used are much higher. Generally, there are formed the respective halides of the saturated hydrocarbons used and of their compounds with aldehydes and ketones. However, these halides may be readily broken down.

In principle, the process is the same in all of the modifications described above since the reaction between the saturated hydrocarbons and the aldehydes or ketones goes first through the carbonyl group. However, as indicated above, the yields resulting from the practice of the several modifications of the process described above are relatively small with the result that these modifications are not suitable for best commercial practice but are more of scientific than commercial interest. For satisfactory commercial practice it is necessary that the process be so conducted as to insure maximum quantitative yields by the use of inexpensive reagents that react directly upon the hydrocarbons and to provide for the recovery of all of these reagents or at least one of them. I have accomplished this desired result by providing a modification of the general process described above by which aldehydes, alcohols, unsaturated compounds, and condensation and polymerization products can readily be produced directly from the hydrocarbons or mixtures thereof and isolated and purified. In this modification, I employ a sulfur oxide or sulfuric acid as the activating agent for the reaction referred to. In commercial practice it is most advantageous to employ sulfuric acid and this material will be used for the purpose of specific illustration in the further description of this modification of the process. While it is ordinarily advisable to use concentrated sulfuric acid as the activating agent, the acid does not have to be concentrated since, for example, even a 75 per cent. acid can activate the reaction. However, the reaction is much slower and, therefore, a concentrated acid is recommended.

As indicated above, I may react with the saturated hydrocarbon to be treated either an aliphatic aldehyde or ketone, sulfuric acid being employed as an activating agent to promote the reaction. The reactions which occur when aldehydes and ketones are employed will be separately considered.

When aliphatic aldehydes act upon a saturated hydrocarbon under the activation of sulfuric acid, polymerization products are mostly formed. However, even under these circumstances it is possible to isolate from the reaction mass certain alcohols and unsaturated compounds formed by the reaction of the saturated hydrocarbons with the aliphatic aldehydes used, not only by the direct method but also by the depolymerization of the products of polymerization.

When it is desired to react upon saturated hydrocarbons either as such or in mixture, such as in crude petroleum or fractions thereof, with an aliphatic aldehyde, strong sulfuric acid being used as an activating agent, it is preferable to employ metaldehydes and paraldehydes. Lower aldehydes can be used in vaporized state when convenient but for obvious reasons, it is much better to use the metaldehydes and paraldehydes directly in connection with strong sulfuric acid.

As a specific example of the modification of the process wherein an aliphatic aldehyde is used in the reaction, I may take one molecular equivalent of comparatively pure hexane and, while cooling the mass, mix it with slightly more than one molecular equivalent of concentrated sul-

furic acid (66° Bé.). There is gradually added to this mixture with careful outside cooling to keep the temperature of the mass at about 5° C. slightly more than one molecular equivalent of 5 paraldehyde calculated as acetaldehyde. In approximately one-half hour the mixture nearly solidifies and the mass is then treated with say soda ash in an amount sufficient to neutralize the sulfuric acid present. As a result of this treatment 10 there is obtained a reddish solid polymerization product formed of hexane and paraldehyde used. This product can be recrystallized, purified and obtained in nearly white state. It is generally quite stable but on heating it ordinarily dissociates, the dissociation mass formed containing from one to three molecules of hexane to one molecule of paraldehyde.

During the foregoing reaction several samples 20 were taken and neutralized before the polymerization product was formed and I have discovered that this reaction goes through the formation of substituted alkynes, alcohols up to the polymerization product. In the particular example set forth, hexylenes and hexyl alcohols were formed 25 as intermediate products. One of the unsaturated hydrocarbons (alkylenes) obtained as an intermediate product was identified as 1 methyl, 2 pentylethylene

30

This reaction was repeated also with paraformaldehyde and other accessible aldehydes. It was also applied to gasoline, the polymerization product of which behaves in a similar way as that of pure hexane. Other hydrocarbons and their mixture, including crude petroleum give the same 35 reaction. In the case of higher aldehydes one or both chains sometimes may be broken but, in principle, the reaction of the carbonyl group is the same. This is also true in connection with the higher ketones.

40 While aliphatic aldehydes may be employed in the practice of the present invention as indicated above, it is preferable to use ketones instead of the aldehydes. From a commercial standpoint, the lowest ketones, and particularly acetone, are best suited for the process. Acetone is 45 hereinafter specified for the purpose of illustration since acetone illustrates to best advantage all of the steps and mechanics of the reaction referred to above and also since all intermediate 50 products leading up to the condensation products can be isolated and the yields are substantially quantitative and the products comparatively pure. While acetone is hereinafter specified for the sake of convenience, it is, of course, to be understood 55 that this compound is used solely for the purpose of specific illustration. Other ketones and also aldehydes react in a generally similar way. Of course, where aldehydes are employed polymerization products are obtained whereas when ketones are employed condensation products are 60 obtained. Also, there is naturally a specific difference between the intermediate products obtained when aldehydes and ketones are used. For example, where acetaldehyde is used, the substituted or additive alkynes produced are 1 65 methyl, 2 alkyl ethylenes whereas when acetone is employed the substituted or additive alkynes are 1,1 dimethyl, 2 alkyl ethylenes or 2 methyl, 2 alkyl ethylenes.

70 75 Where acetone is reacted with a saturated ali-

phatic hydrocarbon or a cycloparaffin in the presence of sulfuric acid under uncontrolled conditions there are formed almost exclusively condensation products of acetone with itself. However, while acetone and all other aliphatic ketones and aldehydes do form a great number of compounds between themselves and the saturated hydrocarbons treated, I have discovered that by controlling and regulating the reaction the production of certain specific products may be obtained. For example, by modifying the concentrations of the hydrocarbon, acetone and sulfuric acid and also by varying the time of treatment and the temperature of operation the production of certain specific compounds may be effected. The regulation and control of the reaction to produce particular compounds will be apparent from the several examples of this modification of the process set forth below.

While in a broad sense the present invention 20 depends upon the reactivity of the carbonyl group in the reaction between an aliphatic aldehyde or a ketone with saturated aliphatic hydrocarbons and cycloparaffins, it also depends specifically upon the formation of substituted or additive alkynes and their subsequent regulated decomposition in different acid and alkali concentrations.

From a scientific standpoint, my process is 30 based upon the formation of carbinols and alkynes and the subsequent direct decomposition and transformation of the alkynes to form alcohols and aldehydes and also polymerization and condensation products. In order that the general scheme or mechanics of the present process 35 may be readily apparent, there is set forth below a series of reactions which may take place when a saturated hydrocarbon is reacted with a ketone in the presence of sulfuric acid. The process may be so conducted that it may be terminated at the 40 end of the first reaction or, as where the production of aldehydes is the goal, all of the reactions will take place successively before the production of the final product. The extent to which the reactions are caused to take place will depend upon the manner in which the treatment is 45 regulated. Generally speaking, the time of treatment and the concentration of hydrocarbon present may be considered as fixed constants and the extent to which the successive reactions occur is 50 primarily dependent upon the increase in the concentration of the ketone and sulfuric acid.

For example, assuming that hexane is reacted 55 with a certain concentration of acetone in the presence of a certain concentration of sulfuric acid, and the reaction product treated with an alkali, such as sodium carbonate, as is hereinafter described in detail, there may be produced as the final product from the hexane and acetone employed an additive carbinol, which may be indicated in a general way as follows:

The foregoing equation is, as stated, merely a general indication of the formation of an additive carbinol from the hexane and acetone employed, which, as specifically pointed out below, may be the result of the total treatment of a saturated hydrocarbon in accordance with the present invention. The equation obviously is not intended to show how the reactions take place in the final 70 75

production of the carbinol, or otherwise serve as a theoretical explanation of the changes taking place during the treatment. In this connection, it is pointed out that the details of the procedure for the production of carbinols of this type are hereinafter specifically set forth, particularly in Example 1.

While it is to be understood that the present invention is not to be construed as being limited by any theory expressed herein, I am setting forth below what appears from numerous experiments and extended research to be the correct theoretical explanation of the several stages of the present process.

When hexane, acetone and sulfuric acid are mixed in the concentrations and under the conditions contemplated by Equation I, which details of procedure are hereinafter specifically described, there appears to be formed a loose complex, which may be considered a pseudoester, as follows:

It further appears that when this loose complex is treated with an alkali, as hereinafter described, it is converted into a carbinol of the type referred to in Equation I, as follows:

By increasing the concentration of acetone and sulfuric acid above that contemplated in Equation I, it may be considered that an additive carbinol, after neutralization, is first produced as indicated generally in Equation I, and that dehydration occurs to yield an additive alkylene, which is indicated in a general way by the following equation:

60 By way of theoretical explanation of the thus indicated production of an additive alkylene, it appears that in the presence of the higher concentration of acetone and sulfuric acid contemplated in Equation II, there is formed a complex of the following structure:

It further appears that in the presence of the alkali under the conditions of treatment described in detail below, reaction occurs in the

following manner to produce an additive alkylene:

In this case, when mobile hydrogen is present, as is the case where there is used in the process acetone or any other ketone having at least a methylene group with one mobile hydrogen adjacent to the carbonyl group, the change indicated in Equation IIb can occur, the dehydration taking place with the mobile hydrogen of the methyl group.

The dehydration might, however, under regulated conditions as described below take place at the hydrocarbon group involving another hydrogen of the hydrocarbon. For example, if there is employed a higher concentration of acetone and sulfuric acid than contemplated in Equation II, or if heat and dry alkali are used in the subsequent treatment as hereinafter described, the additive alkylene produced as generally indicated by Equation II may be converted into an additive iso-alkylene, as indicated in a general way by the following equation:

As indicated, the additive alkylene produced according to Equation II, is transformable into the additive iso-alkylene produced in accordance with Equation III. However, the reaction is not readily reversible. Therefore, it is analogous to the eugenol-isoeugenol transformation to a certain extent.

With reference to the theoretical explanation of the change indicated generally in Equation III, it appears that under the conditions of operation referred to, there is formed a complex of the following structure:

It further appears that upon treatment with alkali, as hereinafter described, an iso-alkylene is formed as follows:

The type of additive alkynes produced in accordance with Equations II and III can be readily changed into carbinols, the isopropyl or isopropylidene group being either changed back to acetone or to isopropyl alcohol, or can be easily oxidized, even to a mixture of acids. The remaining hydrocarbon radicle can either condense to higher hydrocarbons or undergo other changes to form alkynes proper or alcohols.

If, by the adjustment of the concentration of acetone and sulfuric acid the general process is

carried farther than indicated by the preceding equations, alkylene proper may be produced according to the following equation (in which one more carbon atom from the saturated hydrocarbon radicle R is free to show the changes):

10

In connection with the theoretical explanation of the production of an alkylene proper in accordance with Equation IV, it is pointed out that under the conditions of operation referred to, there apparently is formed a complex of the following structure:

20

It further appears that in the subsequent treatment with alkali as hereinafter described in detail, the following reaction takes place:

30

It will be apparent from Equation IVb that in this case there has been complete dehydration. This is due to the excess of alkali present and the action of heat, which may merely be the heat of reaction. It will be further noted that there is also produced an unsaturated compound from acetone, but where even a slight amount of water is present this compound is converted into isopropyl alcohol as follows:

In actual practice, isopropyl alcohol is generally formed and only very small amounts of n-propyl alcohol are observed. Of course, the shifting of the hydrogen atoms in the end hydrocarbon group is a well known phenomenon in organic chemistry due to the action of alkali or heat, or both.

The product resulting from Equation IV can be converted into an alcohol in accordance with the following equation:

With reference to the theoretical explanation of such conversion of a saturated hydrocarbon into an alcohol, it appears that under the conditions of operation hereinafter referred to there is formed a complex of the following structure:

It further appears that in the subsequent treatment in the presence of alkali and water under

the conditions of operation hereinafter described in detail, the following reaction occurs:

The end product indicated in the equation may be isopropyl alcohol, for example.

If desired, the alcohol produced in accordance with Equation V may be converted into an aldehyde in accordance with the following equation:

Referring to the theoretical explanation of the production of aldehydes as indicated in Equation VI, it is to be noted, as hereinafter pointed out in detail, that in the production of aldehydes a very high concentration, usually about nine molecular equivalents, of sulfuric acid must be used. It is believed that more than one mol of acid enters the complex which is produced under the conditions of operation hereinafter described. This complex may be considered as having the following structure:

A possible theoretical explanation in graphic form of the formation of an aldehyde in the subsequent treatment of the suggested complex with alkali, as described below, would be as follows:

As pointed out below under Example 6, substantial excess of alkali should be avoided in the reaction indicated immediately above.

It will be apparent from the above that my process is based (a) upon the formation of carbinols, (in accordance with Equation I), and alkynes (in accordance with Equations II, III and IV) and (b) upon the direct decomposition and transformation of these alkynes to form alcohols (according to Equation V) and aldehydes (according to Equation VII). Polymerization and condensation products may also be formed from the alkynes, as will be apparent.

For the purpose of specific illustration of the several reactions which may be caused to take place when an aliphatic or cyclic saturated hydrocarbon is reacted with an aliphatic aldehyde or ketone in the presence of sulfuric acid, several examples or different embodiments of the process are set forth below.

Example 1

I have found that practically any amount of any aliphatic aldehyde or any aliphatic ketone, especially acetone, together with sulfuric acid,

reacts with aliphatic or cyclic saturated hydrocarbons to give certain amounts, mostly mixtures, of unsaturated compounds and alcohols, aldehydes or polymerization and condensation products. For the present example I have selected a mixture of hydrocarbons nearly gaseous at ordinary temperature as they are found in petroleum ether, mostly pentanes and hexanes. Still lower hydrocarbons can be dissolved in the aldehyde or ketone to be used but in the present case it is unnecessary. In this example the saturated hydrocarbons in petroleum ether are reacted with acetone in the presence of sulfuric acid.

I first take one molecular equivalent of petroleum ether. This equivalent refers back to the pure hydrocarbons and is used in this sense throughout the present description, the fact being emphasized that in each case in order to obtain best results the equivalents must be calculated according to the amounts and purity of the hydrocarbons present. In the present case where petroleum ether is employed, the equivalent means approximately forty parts by volume. The petroleum ether is then mixed with about one-half of one molecular equivalent of sulfuric acid, which in the present case is approximately fifteen parts by volume of concentrated sulfuric acid (66° Bé.). The ether and acid are mixed in a suitable apparatus of the character hereinafter described, which apparatus is suitable for use for all of the reactions hereinafter set forth. When the hydrocarbons and sulfuric acid are mixed the temperature in all cases should be lowered to approximately 5° C.

The apparatus in which the ether and acid are mixed is preferably an acid-proof vessel provided with a mechanical stirrer which is preferably run by motor. The apparatus must either be provided with a water jacket or must be immersed in running water. In the upper part of the apparatus an opening should be provided for the introduction of the materials employed.

Throughout the time of adding and stirring the sulfuric acid with the petroleum ether, the mass should be continuously cooled to about 5° C. as stated above. When the mixing is completed I then add to the cooled mixture very gradually while maintaining the mass at a temperature not substantially in excess of 10° C., not less than one and not more than two molecular equivalents of pure dry acetone. In this example the acetone would be used to the extent of thirty to sixty parts by volume. The addition of the acetone should be gradual and would generally require approximately fifteen minutes, after which the mixing is continued for thirty minutes more. Hence, the total time of treatment from the beginning of the addition of the acetone should be about forty-five minutes. Of course, if more than fifteen minutes were consumed in adding the acetone, the total reaction time should be prolonged proportionately.

Thereafter, while continuing the stirring and cooling, there is added sodium carbonate made into a paste with cool water, until the mixture is completely neutralized. The mixture is then diluted with water in an amount sufficient to dissolve all sulfate and remaining carbonate. In preferred practice the diluting water is made slightly alkaline with caustic soda. Upon dilution a reddish fragment oil rises to the top of the mass and is separated. The product is washed several times with water and preferably fractionated, preferably with reduced pressure.

The apparatus employed in the above described process is preferably provided with a condenser, which may be an ordinary cold water condenser, so that all of the gases and superfluous acetone which might escape during the neutralization treatment as described above, may be condensed and recovered.

The principal products of the above described reaction, to the extent of 60 to 90 per cent., are tertiary carbinols of the type produced in accordance with Equation I set forth above. For the most part the products are 1,1 dimethyl-2-pentyl or 1,1 dimethyl-2-hexyl carbin-1-ols, although I have also isolated dimethyl heptyl and butyl carbinols. There are also formed in the reaction unsaturated additive compounds of the type hereinafter described and compounds formed by the condensation of acetone with the side chains, but the majority of the reaction products are carbinols of the type indicated above in Equation I.

The same reaction with practically the same results in principle is applicable to all other saturated aliphatic and saturated cyclic hydrocarbons and to their mixture in crude petroleum or any fraction or fractions of crude petroleum.

Example 2

Under the same conditions and in the same apparatus as described under Example 1, I mix one molecular equivalent of comparatively pure hexane, with not less than one and not more than two molecular equivalents of concentrated sulfuric acid. To this mixture is added not less than one and not more than two molecular equivalents of pure dry acetone. The temperature of the reaction mass should be kept at about 15° C. and the total time for the reaction is about one hour. At the end of this time the mass is neutralized and diluted in the manner described above and a reddish fragrant oil is separated. By tests it has been determined that this oil is mostly 2 methyloctyl-1-2-ene produced in accordance with Equation II set forth above.

I have found that all primary, secondary and tertiary hydrocarbons undergo the reaction as set forth in Equation II as do also the cyclic paraffins while quaternary hydrocarbons are usually attacked in a side chain having a primary ($-\text{CH}_3$) group. All hydrocarbons of the foregoing type including mixtures thereof in crude petroleum or any fraction or fractions of crude petroleum can be treated in the foregoing manner and give the same or substantially the same results.

Example 3

When the neutralized mixture described in the preceding example is not diluted with water, but sufficient sodium carbonate is added to make it nearly solid, and the resulting mass then mixed with about 10 per cent. of its bulk of powdered dry sodium hydroxide and slowly warmed over asbestos at a temperature of about 50 to 60° C. for about two hours, acetone is evaporated and the additive alkylene produced in accordance with Equation II is changed into its iso-compound. In the present case where hexane was used the compound produced (in accordance with Equation III) is 1,1 dimethyl, 2 pentyl-ethylene. While there are a number of other ways to perform this transformation of the substituted or additive alkynes into their iso-compounds, I prefer to employ the method described.

Example 4

When the original mixture of hexane, concentrated sulfuric acid and acetone described in Example 2 is mixed for about three hours instead of only one hour, as set forth under Example 2, and is then neutralized and diluted, it is found that isopropyl alcohol is formed, or original acetone as the case may be, in the dilute solution and there is also produced an oil which is essentially an alkylene of the type produced in accordance with Equation IV. Where, as in the present case, hexane is originally treated, the alkylene will, of course, be hexylene. There are a number of ways to form this type of alkynes, namely, to keep an additive alkylene or additive isalkylene produced in accordance with Equations II and III in a dilute acid solution of proper strength, say 10 per cent. sulfuric acid, but the method specifically described above is preferred.

The foregoing reactions described in the preceding example are also applicable to any saturated hydrocarbon. Cyclic paraffins give reactions in accordance with Equations I, II and III, but in some cases their cycle can be disrupted, and they also form respective alkynes of straight chain type as produced in accordance with Equation IV. However, as I have found, other changes might take place and an additive isalkylene of the type produced in accordance with the Equation III may be preserved.

Crude petroleum is also changed in the above referred to manner into fragrant oils when products of the type produced in accordance with Equations I, II and IV are present although when a product of the type produced in accordance with Equation III is present it sometimes has quite a disagreeable odor, especially when it is derived from one of the cyclic paraffins. The oils referred to have properties closely approximating the properties of vegetable drying oils and in some cases even surpass them.

As will be apparent, alkynes proper of the type produced in accordance with Equation IV may be used for the production of alcohols, but in their crude mixture there are generally other substances present which give rise to resinification with concentrated sulfuric acid and, therefore, the following method for the production of alcohols is preferred.

Example 5

As a specific example of the formation and production of alcohols through the above described stages, I take one molecular equivalent of comparatively pure decane and mix it under the same conditions and in the same apparatus as described above, with not less than three and not more than four molecular equivalents of concentrated sulfuric acid and then add not less than three and not more than four molecular equivalents of pure dry acetone. The temperature of the mass is maintained at about 15° C. and the time of the reaction is about one hour. The resulting mixture is then neutralized with sodium carbonate in paste form, although here as well as in the processes described other carbonates or hydroxides, such for example, as calcium hydroxide or calcium carbonate can also be used. The neutralized mass is then diluted with water. As a result of this process decyl alcohol is produced.

The same process may be used for mixtures of hydrocarbons or for crude petroleum and its fractions. For example, I may mix forty-five parts

by volume of ordinary commercial gasoline, ninety parts by volume of concentrated sulfuric acid, and ninety parts by volume of pure dry acetone. Sodium carbonate in an amount sufficient to neutralize the acid present is mixed with about fifty parts by volume of cold water and the mixture is neutralized with this paste. About two hundred parts by volume of water are then added. Thereafter steam is circulated through the jacket surrounding the reaction vessel and acetone, isopropyl alcohol and the more volatile alcohols from the gasoline hydrocarbons distill over. The remaining alcohols consisting mostly of amyl, hexyl, heptyl and octyl alcohols are then separated from the mass and are fractionated or otherwise treated. Primary and secondary alcohols are separated in the well known chemical way. The reaction, in general way, is as follows:

For primary alcohols:

For secondary alcohols:

For tertiary alcohols:

Tertiary alcohols may, of course, also be formed in accordance with the Equation I under Example 1. Quaternary hydrocarbons may sometimes cause the resinification of the mixture, but they are preferably attacked in one of their primary ($-\text{CH}_3$) side chain groups to form also primary alcohols.

In an analogous way this is also true in general about the formation of alkynes proper as in Example 4. The original quaternary hydrocarbons or in some cases even the original tertiary hydrocarbons may sometimes form either internal double bonds or be attacked in a primary group ($-\text{CH}_3$) in a side chain. The resulting alcohols formed as in Example 5 are then structurally analogous to the alkynes proper.

As will be apparent the present process is suitable for the treatment not only of hydrocarbons which are liquid at normal temperatures but also hydrocarbons which are either gaseous or solid at normal temperature. When gaseous hydrocarbons are employed they are dissolved in acetone or the like and the process is carried out under pressure. When solid hydrocarbons are treated it is also preferable to dissolve these in the acetone or the like.

In the above example there has been described the treatment of comparatively pure decane and also ordinary commercial gasoline. As will be apparent, the process described is also suitable for the treatment of crude petroleum. Where crude petroleum is treated under approximately the same conditions as described above in connection with the treatment of gasoline, there is produced a very fragrant spicy oil from which solid alcohols separate very readily on cooling. The oil mixture may be used as such or the alcohols may be separated by steam distillation or fractionation.

The formation of alcohols from cyclic saturated hydrocarbons is analogous to the above described

formation of alcohols from the straight chain saturated hydrocarbons. For example, when cyclohexane, which is a typical cyclic paraffin, is reacted with acetone in the presence of sulfuric acid as an activating agent, and the resulting mass neutralized as described above, the formation of alcohol takes place in the following manner:

As is apparent, the three equations set forth immediately above are intended merely to indicate in a general way the production of an alcohol from cyclohexane by the treatment of the same with acetone and sulfuric acid and the subsequent treatment with alkali as described above. The first of the three equations, for example, merely indicates in a general way the end product which results from cyclohexane and acetone during the treatment in the presence of sulfuric acid and the subsequent treatment with alkali. Theoretically, the complete reaction by which the end product in the first of the three equations referred to is formed involves the formation of a complex of the following composition:

50 and the reaction of this complex with alkali, such as sodium carbonate, as follows:

The product thus produced is then converted into an alcohol as indicated in a general way in the second and third of the three equations referred to.

Example 6

The production of all of the above referred to compounds, and especially the production of aldehydes, is relatively easy where higher or solid hydrocarbons contained in fractions of petroleum such as petroleum jellies, paraffin oil, mineral waxes and the like are treated. Much lower molecular equivalents of aldehydes or ketones and sulfuric acid are required in the treatment of such hydrocarbons. Since higher molecular equivalents of aldehydes or ketones and sulfuric acid are required where aldehydes are to be produced from lower hydrocarbons, the production of al-

dehydes will be specifically described in connection therewith.

Where it is desired to produce aldehydes from a mixture of hydrocarbons, say kerosene, the process is carried out in an apparatus similar to that described above and under conditions of reduced temperature as set forth in connection with the preceding example. In a specific case, one molecular equivalent of kerosene, not less than six and not more than nine molecular equivalents of concentrated acid, and not less than four and not more than six molecular equivalents of acetone are mixed together, the mass being stirred and cooled as described above. By way of more specific illustration, sixty parts by volume of kerosene, two hundred and seventy parts by volume of concentrated sulfuric acid and one hundred and fifty parts by volume of acetone are mixed, stirred and cooled.

The reaction is permitted to proceed for about forty-five minutes. Thereafter the acid mass is neutralized, as with sodium carbonate, the alkali employed for neutralization being used only in sufficient amount to react with the acid present. Excessive alkali during the neutralization must be avoided. After neutralization the mass is diluted with water and aldehydes, in some cases mixed with ketones, rise to the top of the mass in the form of an oil of very pleasant odor which is generally pinkish in color. If desired, the whole mixture, that is, the oil and aqueous solution may be filtered to remove solid aldehydes and ketones and also a small proportion of carbinols from the tertiary hydrocarbons and condensation products, mostly from the quaternary hydrocarbons, although I have found that these latter hydrocarbons are generally attacked in their primary side chains to form aldehydes. Cyclic paraffins usually remain in the form of additive double-bonded compounds although the cycle may be readily broken and the respective aldehydes formed. The above reaction proceeds substantially as follows:

It is evident, as shown in the equations, that what takes place is an aldehydo-ketonic disruption of the double bond in the additive-isoalkylene set forth as the starting point in the above equations and which is formed as an intermediate product in accordance with Equations I, II, and III set forth above. Where an aliphatic aldehyde is used in the practice of the process, naturally two aldehydes are formed. Sometimes even acetone may form small quantities of acetic aldehyde in the case described.

The above referred to treatment is applicable to all saturated hydrocarbons and cycloparaffins not only in pure condition but also in mixtures as in crude petroleum or its fractions. With pure hydrocarbons, pure aldehydes are formed. In the event that it is desired to treat gaseous hydrocarbons, it is preferable to dissolve the gases in acetone and gradually add the sulfuric acid. The operation may be performed under pressure and at a temperature of approximately 0° C. and not above 5° C.

Example 7

When sulfuric acid is employed greatly in excess of the amount of the aliphatic aldehyde or ketone employed to react with a saturated hydrocarbon, the reaction which takes place causes the production primarily of higher hydrocarbons formed by the condensation of the hydrocarbons used. For example, one part by volume of a saturated aliphatic or cyclic hydrocarbon either as such or in mixtures may be mixed with one part of acetone and three parts of sulfuric acid. The products formed are mostly higher hydrocarbons. When the amounts of ketone and sulfuric acid are reversed and the ketone is present in substantial excess over the sulfuric acid, double-bonded hydrocarbons are first formed by the reaction of the saturated hydrocarbon with the ketone present and these double-bonded hydrocarbons can absorb another molecule of the ketone at their double bonds and thus additional condensation products may be formed. In the same way, where aliphatic aldehydes are used, higher polymerization products can be formed from saturated aliphatic hydrocarbons and cycloparaffins.

The foregoing is set forth to show that I am perfectly aware of the fact that by other combinations than those specifically described different products may be produced. While I have conducted numerous experiments using all aliphatic aldehydes and ketones which are accessible and have found that practically the same results are obtained therewith, I have specified above for the sake of illustration the aldehydes and ketones by the use of which the desired products can be made most simply and inexpensively and, for that reason, be of greater usefulness in general than those made by the use of less readily accessible or more expensive aldehydes and ketones.

As described in detail above, all of the desired products produced in accordance with the present invention by the reaction of aliphatic aldehydes and ketones with saturated aliphatic hydrocarbons and cycloparaffins in the presence of an activating agent of the character described above are formed as the result of the action of the carbonyl group common to aliphatic aldehydes and ketones upon the saturated hydrocarbon under treatment. Also the formation and production of the products principally desired, such as alcohols and aldehydes depend upon the previous formation of compounds similar to those produced in accordance with Equations I, II, III and IV set forth above, no matter what aliphatic aldehyde or ketone is used and regardless of the proportions employed. Even if polymerization or condensation products are formed the complete reaction involves the several intermediate reactions illustrated by Equations I, II, III and IV appearing above.

As indicated above, there are numerous possible modifications of the general reaction between a saturated hydrocarbon and an aliphatic aldehyde or ketone and an activating agent such as sulfuric acid, with the production of numerous different products. However, as pointed out above, the several reactions which may be caused to take place depend upon the action on the saturated hydrocarbon under treatment of the carbonyl group common to aliphatic aldehydes and ketones. As has been described above, by varying the regulation or control of the general reaction, the various stages through which the reaction may proceed can be controlled. For example, if

it is desired to produce from a saturated aliphatic or cyclic hydrocarbon an additive carbinol by the use of acetone and sulfuric acid, there should in general, be employed one molecular equivalent of the hydrocarbon and up to one-half molecular equivalent of the sulfuric acid. While, in general, there should be employed one molecular equivalent of acetone, the exact amount of acetone employed may be varied. For example, I may use from one to two molecular equivalents of acetone where the quantitative production of carbinols is desired.

Further, when it is desired to produce from an aliphatic or cyclic saturated hydrocarbon, additive alkynes by the use of acetone and sulfuric acid, the materials are employed in the proportions of one molecular equivalent of hydrocarbon, from one to two molecular equivalents of acetone and from one to two molecular equivalents of sulfuric acid. The proportions are the same where it is desired to produce additive isoalkynes, the treatment of the materials in the proportions specified being followed by the heating of the mass with dry alkali.

Further, where it is desired to produce alkynes proper from saturated aliphatic hydrocarbons by the use of acetone and sulfuric acid, the ingredients are mixed in the proportions of one molecular equivalent of hydrocarbon, from one to two molecular equivalents of acetone and from one to two molecular equivalents of sulfuric acid. As will be noted, these proportions are the same as indicated above for the production of additive alkynes and additive isoalkynes. However, as set forth, in the case of the production of additive isoalkynes the treatment involves heating the reaction mass with dry alkali. Where it is desired to produce alkynes proper instead of additive alkynes, the reagents are employed in the same proportions but the reaction is continued from one to three hours.

Further, where it is desired to produce alcohols from alkynes proper, this can be accomplished, as pointed out above, by the use of larger amounts of sulfuric acid in order to form sulfuric acid esters of the respective alcohols and subsequently adding water to cause the esters to break down and liberate the alcohols themselves. In general, when it is desired to produce alcohols in this manner from aliphatic or cyclic saturated hydrocarbons by the use of acetone and sulfuric acid, the materials are mixed in the proportions of one molecular equivalent of hydrocarbon, three to four molecular equivalents of acetone, and three to four molecular equivalents of sulfuric acid.

Further, when it is desired to form aldehydes through the stage of additive isoalkynes of the type produced in accordance with Equation III set forth above, this is accomplished by the addition of greater amounts of sulfuric acid and neutralizing and dissolving the mass in mild alkaline solution, such as sodium carbonate solution. For example, when aldehydes are produced from saturated aliphatic hydrocarbons by the use of acetone and sulfuric acid, the materials are employed in the proportions of one molecular equivalent of hydrocarbon, from four to six molecular equivalents of acetone and from six to nine molecular equivalents of sulfuric acid. As pointed out in detail above in Example 6, this treatment is followed by neutralization and solution in mild alkaline solution.

As will be apparent from the foregoing, all of the products described are obtainable through

the reaction of an aliphatic or cyclic hydrocarbon, an aliphatic aldehyde or ketone and a chemical activating agent such as sulfuric acid, the ingredients being employed in the proportions of one 5 molecular equivalent of hydrocarbon, from four to six molecular equivalents of the reagent containing a carbonyl group, say acetone, and from six to nine molecular equivalents of sulfuric acid.

Where in the subjoined claims the term "water 10 derivative of an oxide" is employed, it is to be understood that the term refers to a compound which may be derived from an oxide by the action of water on it.

The term "activating agent" as employed in 15 the specification and claims is intended to cover an agent which activates or promotes reaction between a saturated aliphatic or cyclic hydrocarbon and an aliphatic aldehyde or ketone whereby polymerization or condensation products are 20 obtained. As pointed out above, where the saturated hydrocarbon is treated according to the present invention with an aldehyde in the presence of an activating agent, polymerization products are obtained, whereas condensation products 25 are obtained by the practice of the present invention when the saturated hydrocarbon is treated with a ketone in the presence of an activating agent. Several different activating agents have been set forth above including those 30 of both scientific and commercial interest. As has been described, sulfur oxides and especially sulfuric acid are the preferred activating agents for commercial practice. As has been pointed out above, some of the activating agents which 35 may be employed combine in what may be considered an intermediate reaction with organic compounds present but, as heretofore stated, the activating agents are readily separated and are not combined in the final product.

40 While I have described in detail the preferred practice of my process, it is to be understood that the details of procedure, the arrangement of steps and the proportions of ingredients may be variously modified without departing from the 45 spirit of the invention or the scope of the subjoined claims.

I claim:

1. In a process of the character described, the 50 step which comprises reacting a hydrocarbon compound selected from the group consisting of saturated aliphatic and saturated cyclic hydrocarbons with at least one molecular equivalent of a reagent containing a carbonyl group selected from the group consisting of aliphatic aldehydes and ketones in the presence of an activating agent, said reagent containing a carbonyl group being predominantly free from water.

2. In a process of the character described, the 55 step which comprises reacting a hydrocarbon compound selected from the group consisting of saturated aliphatic and saturated cyclic hydrocarbons with at least one molecular equivalent of a reagent containing a carbonyl group selected from the group consisting of aliphatic aldehydes and ketones in the presence of an activating agent consisting substantially of a sulfur compound selected from the group consisting of acid-forming sulfur oxides and sulfuric acid, said reagent containing a carbonyl group being predominantly free from water.

3. In a process of the character described, the 60 step which comprises reacting a hydrocarbon compound selected from the group consisting of saturated aliphatic and saturated cyclic hydrocarbons with at least one molecular equivalent

of a reagent containing a carbonyl group selected from the group consisting of aliphatic aldehydes and ketones in the presence of an activating agent consisting substantially of an acid-forming sulfur oxide, said reagent containing a carbonyl group being predominantly free from water.

4. In a process of the character described, the 65 step which comprises reacting a hydrocarbon compound selected from the group consisting of saturated aliphatic and saturated cyclic hydrocarbons with at least one molecular equivalent of a reagent containing a carbonyl group selected from the group consisting of aliphatic aldehydes and ketones in the presence of an activating agent consisting substantially of sulfuric acid, said reagent containing a carbonyl group being predominantly free from water.

5. In a process of the character described, the 70 step which comprises reacting a hydrocarbon compound selected from the group consisting of saturated aliphatic and saturated cyclic hydrocarbons with at least one molecular equivalent of a reagent containing a carbonyl group selected from the group consisting of aliphatic aldehydes and ketones in the presence of an activating agent consisting substantially of an alkali-forming metal compound selected from the group consisting of oxides and hydroxides of alkali-forming metals, said reagent containing a carbonyl group being predominantly free from wa- 75 ter.

6. In a process of the character described, the 80 step which comprises reacting a hydrocarbon compound selected from the group consisting of saturated aliphatic and saturated cyclic hydrocarbons with at least one molecular equivalent of a reagent containing a carbonyl group selected from the group consisting of aliphatic aldehydes and ketones in the presence of an activating agent consisting substantially of an alkali-forming metal oxide, said reagent containing a carbonyl group being predominantly free from water.

7. In a process of the character described, the 85 step which comprises reacting a hydrocarbon compound selected from the group consisting of saturated aliphatic and saturated cyclic hydrocarbons with at least one molecular equivalent of a reagent containing a carbonyl group selected from the group consisting of aliphatic aldehydes and ketones in the presence of an activating agent consisting substantially of an alkali-forming metal hydroxide, said reagent containing a carbonyl group being predominantly free from water.

8. In a process of the character described the 90 step which comprises reacting a hydrocarbon compound selected from the group consisting of saturated aliphatic hydrocarbons and saturated cyclic hydrocarbons with at least one molecular equivalent of an aliphatic ketone in the presence of an activating agent.

9. In a process of the character described the 95 step which comprises reacting a hydrocarbon compound selected from the group consisting of saturated aliphatic hydrocarbons and saturated cyclic hydrocarbons with at least one molecular equivalent of an aliphatic ketone in the presence of an activating agent consisting substantially of a sulfur compound selected from the group consisting of acid-forming sulfur oxides and sulfuric acid.

10. In a process of the character described the 100 step which comprises reacting a hydrocarbon compound selected from the group consisting of saturated aliphatic hydrocarbons and saturated

75

- cyclic hydrocarbons with at least one molecular equivalent of an aliphatic ketone in the presence of an activating agent consisting substantially of an alkali-forming metal compound selected from the group consisting of oxides and hydroxides of alkali-forming metals.
11. In a process of the character described the step which comprises reacting a hydrocarbon compound selected from the group consisting of saturated aliphatic hydrocarbons and saturated cyclic hydrocarbons with at least one molecular equivalent of an aliphatic ketone in the presence of an activating agent comprising sulfuric acid.
12. In a process of treating saturated aliphatic hydrocarbons, saturated cyclic hydrocarbons, and mixtures containing the same, the step which comprises reacting upon the saturated hydrocarbons under treatment with at least one molecular equivalent of acetone in the presence of sulfuric acid.
13. In a process of treating saturated aliphatic hydrocarbons, saturated cyclic hydrocarbons, and mixtures containing the same, the step which comprises subjecting the material under treatment to the action of acetone and sulfuric acid, such agents being present in the proportion of one molecular equivalent of saturated hydrocarbons, from one to five molecular equivalents of acetone, and from one-half to nine molecular equivalents of sulfuric acid.
14. In a process of treating material containing saturated hydrocarbons selected from the group consisting of saturated aliphatic hydrocarbons and saturated cyclic hydrocarbons, the step which comprises intimately contacting the material under treatment with a reagent containing a carbonyl group selected from the group consisting of aliphatic aldehydes and ketones and a chemical activating agent at a temperature of approximately from 0° C. to 15° C., such agents being present in the proportions of one molecular equivalent of saturated hydrocarbons, up to two molecular equivalents of said reagent containing a carbonyl group, and up to two molecular equivalents of the activating agent.
15. In a process of treating material containing saturated hydrocarbons selected from the group consisting of saturated aliphatic hydrocarbons and saturated cyclic hydrocarbons, the step which comprises intimately contacting the material under treatment with acetone and sulfuric acid at a temperature of approximately from 0° C. to 15° C., such agents being present in the proportions of one molecular equivalent of saturated hydrocarbons, up to two molecular equivalents of acetone, and up to two molecular equivalents of sulfuric acid.
16. In a process of the character described, the step which comprises reacting a saturated hydrocarbon compound selected from the group consisting of saturated aliphatic and cyclic hydrocarbons with a reagent containing a carbonyl group selected from the group consisting of aliphatic aldehydes and ketones in the presence of sulfuric acid, such reagents being present in the proportions of one molecular equivalent of saturated hydrocarbon, from one to two molecular equivalents of said reagent containing a carbonyl group, and from one to two molecular equivalents of sulfuric acid.
17. In a process of treating saturated aliphatic hydrocarbons, saturated cyclic hydrocarbons, and mixtures containing the same, the step which comprises subjecting one molecular equivalent of the material to be treated to the action of from

one to two molecular equivalents of acetone and from one to two molecular equivalents of sulfuric acid.

18. A process of the character described which comprises reacting a hydrocarbon compound selected from the group consisting of saturated aliphatic and cyclic hydrocarbons with a reagent containing a carbonyl group selected from the group consisting of aliphatic aldehydes and ketones in the presence of sulfuric acid, such reagents being present in the proportions of one molecular equivalent of hydrocarbon, from one to two molecular equivalents of said reagent containing a carbonyl group, and from one to two molecular equivalents of sulfuric acid, and treat- 15

19. The process of treating saturated aliphatic hydrocarbons, saturated cyclic hydrocarbons, and mixtures containing the same which comprises subjecting the hydrocarbon material under treat- 20

ment to the action of acetone and sulfuric acid, such reagents being present in the proportions of one molecular equivalent of hydrocarbon, from one to two molecular equivalents of acetone, and from one to two molecular equivalents of sulfuric acid, and treating the resulting mass with dry caustic alkali. 25

20. In a process of the character described, the step which comprises intimately contacting for a period of from one to three hours a hydrocarbon 30

compound selected from the group consisting of saturated aliphatic and cyclic hydrocarbons, a reagent containing a carbonyl group selected from the group consisting of aliphatic aldehydes and ketones, and sulfuric acid, such reagents being present in the proportions of one molecular equivalent of hydrocarbon, from one to two molecular equivalents of said reagent containing a carbonyl group, and from one to two molecular equivalents of sulfuric acid. 35

21. In a process of the character described, the step which comprises intimately contacting for a period of from one to three hours a saturated aliphatic hydrocarbon, acetone and sulfuric acid, such reagents being present in the proportions of one molecular equivalent of hydrocarbon, from one to two molecular equivalents of acetone, and from one to two molecular equivalents of sulfuric acid. 40

22. In a process of the character described, the step which comprises reacting a hydrocarbon 50

compound selected from the group consisting of saturated aliphatic and cyclic hydrocarbons with a reagent containing a carbonyl group selected from the group consisting of aliphatic aldehydes and ketones in the presence of sulfuric acid, such reagents being present in the proportions of one molecular equivalent of hydrocarbon, from three to four molecular equivalents of said reagent containing a carbonyl group, and from three to four molecular equivalents of sulfuric acid. 55

23. In a process of treating saturated aliphatic hydrocarbons, saturated cyclic hydrocarbons, and mixtures containing the same, the step which comprises subjecting the hydrocarbon material under treatment to the action of acetone and sulfuric acid, such agents being present in the proportions of one molecular equivalent of hydrocarbon, from three to four molecular equivalents of acetone and from three to four molecular equivalents of sulfuric acid. 65

24. A process of the character described which comprises reacting a hydrocarbon compound selected from the group consisting of saturated aliphatic and saturated cyclic hydrocarbons with at 75

5 least one molecular equivalent of a reagent containing a carbonyl group selected from the group consisting of aliphatic aldehydes and ketones in the presence of an activating agent selected from the group consisting of acid-forming sulfur oxides and sulfuric acid, said reagent containing a carbonyl group being predominantly free from water, and thereafter treating the resulting mass with alkali.

10 25. The process of treating saturated aliphatic hydrocarbons, saturated cyclic hydrocarbons and mixtures containing the same which comprises subjecting the hydrocarbon material under treatment to the action of at least one molecular equivalent of a reagent containing a carbonyl group selected from the group consisting of aliphatic aldehydes and ketones in the presence of sulfuric acid, said reagent containing a carbonyl group being predominantly free from water, and thereafter treating the mass with alkali.

15 26. In a process of the character described, the step which comprises reacting a hydrocarbon compound selected from the group consisting of saturated aliphatic and cyclic hydrocarbons with 20 25 a reagent containing a carbonyl group selected from the group consisting of aliphatic aldehydes and ketones in the presence of sulfuric acid, such

agents being present in the proportions of one molecular equivalent of hydrocarbon, from four to six molecular equivalents of said reagent containing a carbonyl group, and from six to nine molecular equivalents of sulfuric acid.

5

27. The process which comprises reacting a hydrocarbon compound selected from the group consisting of saturated aliphatic and cyclic hydrocarbons with a reagent containing a carbonyl group selected from the group consisting of aliphatic aldehydes and ketones in the presence of sulfuric acid, such agents being present in the proportions of one molecular equivalent of hydrocarbon, from four to six molecular equivalents of said reagent containing a carbonyl group, and 15 from six to nine molecular equivalents of sulfuric acid, thereafter neutralizing the mass with alkali, and diluting the resulting mass with water.

10

28. The process which comprises intimately contacting one molecular equivalent of a saturated 20 aliphatic hydrocarbon, from four to six molecular equivalents of acetone, and from six to nine molecular equivalents of sulfuric acid, thereafter neutralizing the mass with alkali, and diluting the resulting mass with water.

25

JOSEPH J. PELC.
